UNITED STATES PATENT OFFICE.

JOHN C. McDONALD, OF NEW YORK, N. Y.

RAILWAY-TRAIN-CONTROL SYSTEM.

1,205,462.

Specification of Letters Patent. Patented Nov. 21, 1916.

Application filed August 27, 1915. Serial No. 47,581.

To all whom it may concern:

Be it known that I, JOHN C. McDONALD, a citizen of the United States of America, and a resident of New York, in the county of New York and State of New York, have invented a certain new and useful Railway Train-Control System, of which the following is a specification.

My invention relates to improvements in railway train control systems and particularly to combined train-stopping and speed-control systems.

I have illustrated my invention particularly as applied to electric roads wherein the trains are operated by electric motors deriving current from a third rail or other conductor other than the track rails; but it will be apparent that the system is equally applicable to roads whereon the trains are operated by steam or other motive power other than electricity.

In the following description I will generally refer to the conductor from which the trains receive current for motive power and for control, as the "third-rail"; but it will be understood that any other conductor, for example, an over-head trolley wire, may be substituted for what is, strictly speaking, a third rail, without departure from my invention.

My invention comprises controlling circuits and instruments, the latter being, generally, of the nature of relays, and I have illustrated the track relay of each block as controlled by track circuits; though other well known means for the control of such relays may obviously be employed.

My invention further comprises train circuits and instruments carried by the trains passing over the track.

The objects of my invention are to facilitate the operation of railways; to reduce the liability to collision; to provide simple and effective means for the control of speed; to provide simple and effective means for positively stopping trains; to prevent entry of trains into blocks which are already occupied; to maintain proper block intervals between trains with provision permitting, under exceptional circumstances, (such for example as the stalling of a train ahead) the passage of a train into a block already occupied; to make the system readily applicable to existing railways; and generally to make the circuits and apparatus of the system simple and reliable, and to cause such

circuits and apparatus to afford ample protection.

I will now proceed to describe my invention with reference to the accompanying drawings, and will then point out the novel features in claims.

Figure 1 is a diagrammatic view showing circuits and instruments for one track of a double track railway, the direction of normal progress along such track being indicated by an arrow. Fig. 2 is a diagram of train circuits which may be employed in connection with the circuits shown in Fig. 1. Fig. 3 is a diagrammatic view similar to Fig. 1, showing however an arrangement employing alternating current for propulsion current and direct current for train-control current. Fig. 4 is a diagram of train circuits which may be employed in connection with the circuits shown in Fig. 3. Fig. 5 is a diagrammatic view similar to Figs. 1 and 3, but showing an arrangement employing alternating current of one frequency for propulsion and alternating current of another frequency for train control current, and Fig. 6 is a diagram of train circuits which may be employed in connection with the circuits shown in Fig. 5.

In the embodiment of my invention herein illustrated and described, one at least of the two parallel rails of each track is insulated from the ground and divided into block sections, such sections being insulated from each other. The length of such track sections will depend upon traffic conditions and may be determined readily by those skilled in the art. The third rail is also, preferably, divided into block sections, corresponding generally to the division of the track rail into block sections as above described, the sections of the third rail being not necessarily, however, absolutely co-terminous with the corresponding sections of the track rail.

Referring now to Fig. 1: R¹ and R² designate track rails of which R¹ is shown divided into block sections 2, 3, 4, etc. For each such block there is a corresponding track relay TR², TR³, etc. I have not illustrated a track relay for block 2, but it will be understood that the same instruments and circuits are provided for each block. For each block there is also another relay, commonly termed a line relay, and designated by reference characters L², L³, etc. (It will be understood that the term "relay" is

employed herein in a generic sense, as inclusive of any type of electrically controlled switching means.) I have illustrated the track relays TR^3 and TR^4 , etc., as controlled by track circuits 7 in the ordinary manner, each of which circuits will be shunted by the wheels and axles of a train present on the corresponding block, so as to deenergize the corresponding track relays TR^3 , TR^4 , etc. T designates the third rail, and F a direct current feeder for the several sections of this third rail. In the system as illustrated in Figs. 1 and 2, the use of direct current for motive power is contemplated, and the use of alternating current for train control is contemplated, and therefore the sections of the third rail T are connected by inductive bonds I^3 , I^4 , etc., which permit the passage of the direct power current, but substantially prevent the passage of the alternating train control current. O designates a common return conductor for the train control circuits and S^3 , S^4 , etc., designate transformers, one for each block section, supplying alternating current for the train control circuits. SX designates the conductor supplying the alternating current to the primary coils of these transformers.

The line relays L^3 , L^4 , etc., are "time element" or delay action relays; that is to say, a predetermined interval of time is required for the closing of contact by these relays following the energization of their magnets. Such delay action relays are well known, and I do not limit myself to the use of any particular type of such relay; but as a diagrammatic illustration of the delay action character of these relays I have shown the armature of each such relay as provided with a controlling dash-pot D . It is well known that by means of such a dash-pot employing either liquid or air as the impeding medium, the time required for the closing of contact by the relay may be anything desired within reasonable limits.

Each of the relays TR^3 , TR^4 , etc., has three independent armature contact points a , b , and c , with corresponding fixed contact points.

The circuits will be best understood by describing the operation of the system.

Suppose a train to enter block 3 from block 2. As soon as the wheels of that train enter block 3, the track circuit controlling relay TR^3 will be shunted, deenergizing the magnet of relay TR^3 , and permitting its armature contacts to drop back. Upon the deenergization of relay TR^3 a circuit will be completed from point 8 of common return conductor O through armature contact a of relay TR^3 and the back contact of that armature through conductor D^4 and the magnet of line relay L^4 , and thence, through conductor C^4 , to the c armature of a track relay of a block ahead (in

this case the track relay TR^6 of the second block ahead) and (this block 6 being understood to be clear) through the c armature contact of relay TR^6 , and the corresponding front contact stop, and the armature contact d of the corresponding relay L^6 and the corresponding rear contact, through the secondary winding s^1 of the transformer S^6 to return conductor O and thence back to starting point 8. By the completion of this alternating current circuit the relay L^4 will be energized (it will be understood that these relays L^3 , L^4 , etc., are alternating current relays as well as delay action relays) and therefore the armatures of relay L^4 will be attracted; but since this relay L^4 is a delay action relay, a predetermined interval of time will elapse following the energization of the magnet of this relay L^4 , before contact is made with the front contact of that relay L^4 . Should the train so entering block 3 proceed through that block at a speed greater than that for which delay action relay L^4 has been timed, such train will reach the entrance of block L^4 before the front contact of relay L^4 has been made; in which case (since the front contact of this relay L^4 controls the supply of alternating current from secondary s^2 of transformer S^4 to section T^4 of the third rail, and to the track rail R^2) there will be no alternating current on third rail section T^4 , and, therefore, by means hereinafter described the train will be brought to rest at the entrance of block 4. If, however, the train in block 3 proceeds through that block at a speed not greater than that for which relay L^4 has been set, by the time that train has reached the entrance of block 4 relay L^4 will have closed its front contact, and thereby alternating current from secondary coil s^2 of the transformer S^4 will be supplied through the front contact of that relay L^4 to the third rail section T^4 , thereby permitting the train to proceed, as hereinafter described with reference to the circuits and instruments carried by the train. But now suppose that at the time the train starts to pass from block 2 into block 3, block 6 is occupied. In that event, when the first mentioned train starts to enter block 3, the magnet of track relay TR^6 will be deenergized, and the circuit of conductor C^4 through the c armature of relay TR^6 , and the front contact corresponding to that armature, will be broken; consequently, the magnet of relay L^4 will not be energized upon the entry of the first mentioned train into block 3, and, when the train proceeds through block 3 and reaches the entrance of block 4, relay L^4 will not have closed the alternating current circuit to the third rail section T^4 (supposing block 6 still to be occupied, or not to have been vacated for a time corresponding to that to which relay

L^4 has been set) and therefore the train seeking to enter block 4 from block 3 will be brought to rest by the means hereinafter described.

- 5 When the first mentioned train passes from block 2 into block 3, the magnet of relay L^3 will, in general, already have been energized and the alternating circuit from secondary s^2 of transformer S^3 will have 10 been applied to third rail section T^3 through the front contact of relay L^3 ; similarly, when the train enters block T^4 relay L^4 will already have been energized by the action of relay TR^3 as previously described; when 15 the train has passed completely into block 4 the b armature of relay TR^4 will maintain the circuit through the magnet of relay L^4 —such provision being necessary since, when the train passes completely out 20 of block 3 the magnet of relay TR^3 will be energized and its armature contacts held in attracted position. When the train has passed completely out of block 4 the magnet of relay TR^4 will be energized in turn, 25 its armature contact points held in attracted position, and, therefore, the magnet of relay L^4 will be deenergized.

It will be seen that by the expedient of extending backward the circuit of each line 30 relay L^3 , L^4 , etc., to a contact of a track relay corresponding to a preceding block, I obtain a control of the speed of the train passing through that preceding block; for should the train exceed the predetermined 35 speed it will be arrested upon entry into the block to which the particular line relay under consideration belongs.

Referring now to Fig. 2, showing the instruments and circuits provided on a car 40 or cars of the train to be controlled: 9—9 designates contact shoes adapted to make contact with the third rail T , 10 designates the train line bus, having in it an impedance bond 10', and 11 designates a conductor 45 connected to the contact shoes 9 and also connected to the train line bus through the impedance bond 10'. 12 designates the air brake line, 13 a circuit breaker, controlling the circuit 14—15 leading to the 50 circuit controller of the car, and 16 designates a combined electrically operated valve and relay which, as a valve, controls the air brake line 12. At the operating station or 55 stations of the car I provide a combined valve and switch 17 or 17', also another combined valve and switch 18 or 18'. In most cases motor cars, electric locomotives, etc., are arranged for operation from either end, and therefore two operating 60 positions are provided; consequently, in Fig. 2, I have shown two valve switches 17 and 17' respectively, also two other valve switches 18 and 18' respectively. I have shown the valve 17 in the open or "running" 65 position, that being the position which that

valve should occupy when the car is to be controlled from the end at which that valve 17 is located; and correspondingly, the valve 17' is shown in the closed or "non-running" position. Both valves 18 and 18' 70 are normally in the open position. The fact that the valve 17 is shown in the open position does not necessarily result in the application of the air brakes, for the valve of relay 16 is normally closed.

In the operation of the circuits and instruments shown in Fig. 2, direct current passes from the third rail T of Fig. 1 through one or more of the shoes 9 and thence through conductor 11 and the impedance bond 10' to conductor 10, and thence through conductor 19 to the armature of valve relay 16 and through the front stop of that relay and the magnet coil of circuit breaker 13 to the frame of the car 80 and so to the wheels and axles and track rail R^1 ; thence through one or another of conductors 20 (Fig. 1) back to the secondary s^2 of the transformer from which such train control current was derived. 85 The alternating current in the third rail T also passes through one or more of the shoes 9, and wire 11, to contact point 21 of switch 17' and thence through the arm of that switch and contact point 22 to the magnet coils of relay 16 and thence to ground at 20. When two or more cars are coupled together to form a train, it is customary to connect the train line buses of the cars; and in such case both switches 17 and 17' of cars other than that from which the train is operated should be in the position in which switch 17' is shown in Fig. 2. 90

The impedance bond 10' prevents the alternating current from passing through the train bus 10 of the one car to a corresponding train bus of another car, while permitting passage of direct current from the train bus of one car to the train bus of another car and so on. The alternating current so received through one or another of the shoes 9, and passing through conductor 11 and contact points 21 and 22 of switch 17 passes thence through the conductor 23 and condenser 24 to the magnet coils of valve relay 16 and thence to ground at 20; this magnet being held energized and its air brake valve closed, so long as the supply of alternating current continues. But should the alternating current fail (as will occur, for example, when the car or train exceeds predetermined speed and passes into a block before the delay action line relay L^3 or L^4 etc., of that block has closed its front contact) then the resulting deenergization of the magnet of valve relay 16 will cause the air brake valve of that relay to open, so applying the brakes, and at the same time will release the armature of circuit breaker 13, thus cutting off power current from the 100 105 110 115 120 125 130

motors, and so stopping the car or train. Upon reestablishment of supply of alternating current, the magnet of valve relay 16 will be energized again, thus closing the 5 air brake valve of that relay and closing the circuit through the coils of the circuit breaker 13. This circuit breaker may be understood to be one the armature of which is restored by hand.

10 The condenser 24 excludes direct current from the magnet of air brake valve relay 16.

The valve switches 18 and 18' are provided to permit a train to proceed in case 15 of necessity, even though the alternating train-control current is cut off. These switches 18 and 18' are shown as of the push-button type; though of course they may be of any type. Depressing one of

20 these switches closes the corresponding air brake line valve forming a part of that switch. Supposing the car, the circuits of which are shown in Fig. 2, to be operated from the right hand end (switches 17 and 25 17' being then in the positions shown in Fig. 2) and supposing the car to have been arrested through breaking of the alternating current circuit by one of the line relays L³, L⁴, etc.; in that case the magnet of relay

30 16 will be deenergized and the air brake valve of that relay open, the brakes being applied and the circuit breaker 13 also being open: the operator depresses the switch 18, so closing the air brake line and releasing 35 the brakes. In so doing he closes a circuit 25—26 across the terminals of conductors 14 and 15, so accomplishing the same result as if the circuit breaker 13 were closed; the car or train being thereby 40 permitted to proceed.

Eventually, a condenser 27 (Fig. 1) may be interposed in the train-control-circuit to exclude propulsion current from the train control circuit.

45 Current for the track circuits may be derived from any suitable source; but I have indicated each transformer S³, S⁴, etc., as provided with a third secondary coil s³ connected to the track rails of the corresponding block.

While the use of direct current for propulsion current, and alternating current for train control current, has many advantages, yet in a broad sense it is immaterial which 55 type of current be used for propulsion, and which type for train control. In Figs. 3 and 4 I have indicated an arrangement wherein direct current is employed for train control and alternating current for propulsion. R¹ and R² are, as before the track rails, R¹ being divided into block sections, and T is the third rail or train-control conductor, likewise divided into block sections. F' is the alternating current feed 60 line for propulsion current, and S' the line

through which direct train control current is supplied. L³, L⁴, etc., are direct current line relays and TR³ and TR⁴, etc., are direct current track relays. The circuits are substantially the same as above described 70 with reference to Figs. 1 and 2, except that the several sections of the third rail are connected through condensers 28 which permit the passage of the alternating propulsion current, but excluding the direct train 75 control current. Also, inductive resistances 29 are interposed in the train control circuits to exclude the alternating propulsion current from such circuits. Referring to Fig. 4, in the train line bus 10' condensers 80 30 are provided for excluding the direct train control current from that bus, and inductive resistance 31 is provided in the circuit of the valve relay 16' for excluding the alternating propulsion current from that 85 relay.

Obviously, instead of employing direct and alternating current, either the direct or alternating current being employed for propulsion, and the other current employed 90 for train control, alternating currents of different frequencies may be employed, one for propulsion and the other for train control. This is illustrated in Figs. 5 and 6, wherein a low frequency generator G, say of twenty-five cycles, for example, is provided for supply of propulsion current, and a higher frequency generator G', say from sixty cycles upward, is employed for the supply 95 of train control current. Suitable condensers and inductive resistances are included in the propulsion circuit and in the train control circuits, to make each circuit resonant to the current of the particular frequency pertaining to that circuit and thereby to 100 exclude from such circuit the current of the other frequency. The circuits of Figs. 5 and 6 will be understood readily from consideration of the previous figures.

What I claim is:

1. A railway train control system comprising in combination a track, a conductor extending along said track and divided into block sections, means for the supply of train control current for each such block, comprising a time-element circuit controller, and train actuated means for each block, each such train actuated means controlling the said time-element circuit controller of its own block and the said time-element circuit controller of a block in advance. 110

2. A railway train control system comprising in combination a track, a conductor extending along said track and divided into block sections, means for the supply of train control current for each such block comprising a time-element circuit controller, and train actuated means for each such block, each such train actuated means controlling the said time-element circuit controller of 115 its own block and the said time-element circuit controller of a block in advance. 120

130

its own block, and the said time-element circuit controller of a block in advance, and the said time-element circuit controller of a block in rear.

5 3. A railway train control system comprising in combination a track, a conductor extending along said track and divided into block sections, means for the supply of train control current for each such block comprising a time-element circuit controller, and train actuated means for each such block, each such train actuated means controlling the said time-element circuit controller of its own block, and the said time-element circuit controller of a block in advance, and the said time-element circuit controller of a block in rear, the time-element circuit controller of each block also controlling the time-element circuit controller of a block in rear.

20 4. A railway train control system comprising in combination a track, a conductor extending along said track and divided into block sections, means for the supply of train control current for each such block comprising a time-element circuit controller, and train actuated means for each such block, each such train actuated means controlling the said time-element circuit controller of its own block, and the said time-element circuit controller of a block in advance, and the said time-element circuit controller of a block in rear, the train actuated means and time-element circuit controller of each block jointly controlling the time element circuit controller of a block in rear.

25 5. A railway train control system comprising in combination a track, a conductor extending along said track and divided into block sections, means for the supply of train control current for each such block, comprising a time-element relay and train actuated means for each block and a circuit controlled thereby and passing through the magnet of the time-element relay of a block in advance.

30 6. A railway train control system comprising in combination a track, a conductor extending along said track and divided into block sections, means for the supply of train control current for each such block, comprising a time-element relay and train actuated means for each block and a circuit controlled thereby and passing through the magnet of the time-element relay of a block in advance, each such train actuated means also controlling the time-element relay of its own block.

35 7. A railway train control system comprising in combination a track, a conductor extending along said track and divided into block sections, means for the supply of train control current for each such block, comprising a time-element relay, and train actuated means for each block, and a circuit for

each time-element relay passing through a contact of the train actuated means of a block in rear and through contacts of the train actuated means and time-element relay of a block in advance.

40 8. A railway train control system comprising in combination a track, a conductor extending along said track and divided into block sections, means for the supply of train control current for each such block, comprising a time-element relay, and train actuated means for each block, and a circuit for each time-element relay passing through a contact of the train actuated means of a block in rear and through contacts of the train actuated means and time-element relay of a block in advance, each such train actuated means comprising means for holding the time-element relay of the corresponding block in position for the supply of train control current to that block.

45 9. A railway train control system comprising in combination a track, a contact conductor extending along said track and divided into block sections, circuits, one for each such block, for the supply of train control current to the several blocks of that conductor, a delay action relay for each such block section controlling the corresponding train-control current circuit, means located at a predetermined distance in advance of each such block section, and arranged to be actuated by a passing train and when so actuated to cause the relay corresponding to such block to act to close the train control circuit of that block, and means for holding each such relay in closed circuit position during the passage of a train through its corresponding block section.

50 10. A railway train control system comprising in combination a track, a contact conductor extending along said track and divided into block sections, circuits, one for each such block, for the supply of train control current to the several blocks of that conductor, a delay action relay for each such block section controlling the corresponding train control current circuit, a second relay for each such block section and operating means therefor arranged to cause such relay to be operated by a passing train, and a circuit connecting each such second relay to the delay action relay of a block ahead, each such second relay arranged when actuated by a passing train to cause the delay action relay of the said block ahead to act to close the corresponding train control circuit of that block, each such second relay also arranged when actuating by a passing train to hold in closed circuit position the delay action relay of its own block.

55 11. A railway train control system comprising in combination a track, a contact conductor extending along said track and divided into block sections, circuits, one for

each such block, for the supply of train control current to the several blocks of that conductor, a delay action relay for each such block section controlling the corresponding train control current circuit, a second relay for each such block section and operating means therefor arranged to cause each such second relay to be operated by a passing train, and a circuit connecting each such second relay to the delay action relay of a block ahead and thence extending through a normally closed contact of the second relay of a further advance block and through a normally closed contact of the delay action relay of such further advance block, each such second relay arranged, when actuated by a passing train, to cause the delay action relay of the said block ahead to act to close the corresponding train control circuit of that block, provided the said advance block be not occupied, each such second relay further comprising means for holding in closed circuit position the said delay action relay of its own block while that block is occupied.

12. A railway train control system comprising in combination a track, a contact conductor extending along said track and divided into block sections, means for the supply of train control current and propulsion current to each block, such train control current and propulsion current being the one an alternating current and the other a direct current, a delay action relay for each such block section controlling the supply of train control current to that block, a second relay for each such block section and operating means therefor arranged to cause each such second relay to be operated by a passing train, and a circuit connecting each such second relay to the delay action relay of a block ahead and thence extending through a normally closed contact of the second relay of a further advance block and through a normally closed contact of the delay action relay of such further advance block, each such second relay arranged, when actuated by a passing train, to cause the delay action relay of the said block ahead to act to close the corresponding train control circuit of that block, provided the said advance block be not occupied, each such second relay further comprising means for holding in closed circuit position the said delay action relay of its own block while that block is occupied.

13. A railway train control system comprising in combination a track, a contact conductor extending along said track and divided into block sections, means for the supply of train control current and propulsion current to each block, such train control current and propulsion current being the one an alternating current and the other a direct current, said contact conductor com-

prising means permitting the passage of propulsion current from section to section and for preventing passage of train control current from section to section, a delay action relay for each such block section controlling the supply of train control current to that block, a second relay for each such block section and operating means therefor arranged to cause each such second relay to be operated by a passing train, and a circuit connecting each such second relay to the delay action relay of a block ahead and thence extending through a normally closed contact of the second relay of a further advance block and through a normally closed contact of the delay action relay of such further advance block, each such second relay arranged, when actuated by a passing train, to cause the delay action relay of the said block ahead to act to close the corresponding train control circuit of that block, provided the said advance block be not occupied, each such second relay further comprising means for holding in closed circuit position the said delay action relay of its own block while that block is occupied.

14. In a railway train control system, the combination with a conductor extending along the railway track and divided into block sections, means for the supply of propulsion current to that conductor, and means for the supply of train control current to that conductor and for the control of such train control current to effect control of a train, said propulsion current and train control current being the one direct current and the other alternating current, of train equipment comprising contact means adapted to make contact with that conductor, a train control relay and a circuit therefor connected to said contact means, said circuit comprising means for excluding the propulsion current from said train control relay, and brake-operating means and power-controlling means controlled by that relay, and means arranged when operated to make ineffective the operation of such brake-operating means and power-controlling means.

15. In a railway train control system, train equipment comprising contact means adapted to make contact with a conductor extending along a track, a train-control relay and a circuit therefor connected to said contact means, a brake-line containing a valve operated by said relay, and one or more brake-line valve switches each arranged in one position to open the brake-line beyond the relay-operated valve and in such position to close a contact in said relay circuit, and in another position to close said brake-line and open a contact in such relay circuit.

16. In a railway train control system, train equipment comprising contact means adapted to make contact with a conductor ex-

tending along a track, a train-control relay and a circuit therefor connected to said contact means, said circuit including means for the exclusion of propulsion current from said relay, a brake-line containing a valve 5 operated by said relay, and one or more brake-line valve switches each arranged in one position to open the brake-line beyond the relay-operated valve and in such position to close a contact in said relay circuit, and in another position to close said brake-line and open a contact in such relay circuit.

17. In a railway train control system, train equipment comprising contact means adapted to make contact with a conductor extending along a track, a train control relay and a circuit therefor connected to said contact means, said circuit including means for the exclusion of propulsion current from said relay, a brake-line containing a valve 15 operated by said relay, a circuit breaker also controlled by said relay, and a plurality of brake-line valve switches each arranged in running position to open the brake-line beyond the relay-operated valve and in such position to close a contact in said relay circuit, and in another position to close said brake-line and open a contact in such relay circuit, said switches arranged when in the 20 non-running position to close a shunt across the said circuit breaker.

18. A railway train control system comprising in combination a track, a conductor extending along such track and divided into block sections, means for the supply of train 35 control current for each such block, comprising a time-element circuit controller, train actuated means for each block, each such train actuated means controlling the said time element circuit controller of its own block, and the said time-element circuit controller of a block in advance, train equipment comprising contact means adapted to make contact with that conductor, a 40 train control relay and a circuit therefor connected to said contact means, and brake-operating means and power-controlling means controlled by that relay.

19. A railway train control system comprising in combination a track, a conductor extending along such track and divided into block sections, means for the supply of train control current for each such block, comprising a time-element circuit controller, train actuated means for each block, each such train actuated means controlling the said 55 time-element circuit controller of its own block, and the said time-element circuit controller of a block in advance, train equipment comprising contact means adapted to make contact with that conductor, a train control relay and a circuit therefor connected to said contact means, and brake-operating means and power-controlling 60 means controlled by that relay, and means

arranged when operated to make ineffective the operation of such brake-operating means and power-controlling means.

20. In a railway train control system, the combination with a conductor extending 70 along a railway track and divided into block sections, means for the supply of propulsion current to that conductor, and means for the supply of train control current to that conductor and for the control of such train 75 control current to effect control of a train, said propulsion current and train control current being the one direct current and the other alternating current, of train equipment comprising contact means adapted to 80 make contact with that conductor, a train control relay and a circuit therefor connected to said contact means, said circuit comprising means for excluding the propulsion current from said train control relay. 85

21. In a railway train control system, the combination with a conductor extending along a railway track and divided into block sections, means for the supply of propulsion current to that conductor, and means 90 for the supply of train control current to that conductor and for the control of such train control current to effect control of a train, said propulsion current and train control current being the one direct current and 95 the other alternating current, of train equipment comprising contact means adapted to make contact with that conductor, a train control relay and a circuit therefor connected to said contact means, said circuit comprising means for excluding the propulsion current from said train control relay, and brake-operating means and power-controlling means controlled by that relay. 100

22. A railway train control system comprising in combination a track, a conductor extending along said track and divided into block sections, means for the supply of propulsion current to said conductor, means for the supply of train control current to each 105 block of such conductor, comprising a time-element circuit controller, and train actuated means for each block, each such train actuated means controlling the said time-element circuit controller of its own block, and the said time-element circuit controller of a 110 block in advance, means for excluding the train control current supply to any one block from the adjacent blocks, and train equipment comprising contact means adapted to make contact with that conductor, a train control relay and a circuit therefor connected to said contact means, said circuit comprising means for excluding the propulsion current from said train control relay, 115 and means controlled by said train control relay for the control of the train. 120

23. In a railway train control system, train equipment comprising two contact means insulated one from the other and 125

adapted the one to make contact with one conductor extending along a track, and the other to make contact with another conductor extending along such track, a train-control relay and an energizing circuit therefor connected at opposite ends to said two contact means, brake-controlling means operated by said relay, and one or more switches controlling the energizing circuit of said relay and also controlling brake-applying means.

24. In a railway train control system, train equipment comprising two contact means insulated one from the other and one adapted to make contact with one conductor extending along a track, and the other adapted to make contact with another conductor extending along such track, a train-control relay and an energizing circuit therefor connected at opposite ends to said two contact means, a brake-line containing a valve operated by said relay, and one or more brake-line valve switches controlling the energizing circuit of said relay and each arranged in one position to open the brake line beyond the relay-operated valve and in such position to close a contact in such relay energizing circuit, and in another position to close such brake line and open a contact in such relay circuit.

25. In a railway train control system,

train equipment comprising two contact means insulated one from the other and one adapted to make contact with one conductor extending along a track, and the other adapted to make contact with another conductor extending along such track, a train-control relay and an energizing circuit therefor connected at opposite ends to said two contact means, a brake-line containing a valve operated by said relay, and one or more brake-line valve switches controlling the energizing circuit of said relay and each arranged in one position to open the brake line beyond the relay-operated valve and in such position to close a contact in such relay energizing circuit, and in another position to close such brake line and open a contact in such relay circuit, a train control circuit controlled by said train control relay, and one or more emergency valve switches arranged when operated to close the brake line and to close a bridge across the train-control circuit contacts of said relay.

In testimony whereof I have signed this specification in the presence of two subscribing witnesses.

JOHN C. McDONALD.
